UNITED STATES PATENT OFFICE.

NAPOLEON DUSSAULT, OF MONTREAL, CANADA.

NAIL-MAKING MACHINE.

SPECIFICATION forming part of Letters Patent No. 701,178, dated May 27, 1902.

Application filed April 15, 1901. Serial No. 55,804. (No model.)

To all whom it may concern:

Be it known that I, NAPOLEON DUSSAULT, a citizen of the United States of America, residing in the city and district of Montreal, Province of Quebec, Canada, have invented certain new and useful Improvements in Nail-Making Machines; and I do hereby declare that the following is a full, clear, and exact description of the invention, such as will enable others skilled in the art to which it appertains to make and use the same.

My invention relates to improvements in nail-machines; and one object thereof is the provision of a simple, efficient, and automatic machine adapted to the work of pointing and heading nails, so as to produce them in a continuous strip or, as it has been termed, a "string," although the machine may be adapted to the manufacture of detached nails.

20 A further object of the invention is to provide a novel form of the header mechanism by which the nail-heads of a strip or string may easily and rapidly be produced owing to a peculiar movement imparted to the heading-dies.

30 A further object of the invention is to provide a novel shaping and pointing mechanism arranged to give the desired tapered form and penetrating point by compression of the wire stock at proper intervals as distinguished from a filing, cutting, or other similar operation involving transverse abrasion of the metal, thus producing a more solid and generally superior article.

35 A further object of the invention is to improve the construction of the header mechanism with a view to securing rapidity in opening the dies, to the end that ample clearance will be provided for the nail-heads and 40 the stock may be properly and unobstructedly fed through the machine.

Further objects of the invention are to provide a simple feed mechanism for the stock material, to provide for adjustment of the 45 header mechanism and of the feed mechanism, so as to make nails which may vary in length, to simplify the construction, and to arrange the parts so as to secure high speed and maximum efficiency in service, thus increasing the daily output of the machine.

With these ends in view the invention consists in the novel combination of mechanisms

and in the construction and arrangement of the various parts for service, which will be hereinafter fully described and claimed.

55

In the drawings hereto annexed, forming a part of this specification, Figure 1 is a plan view of a nail-machine embodying my invention. Fig. 2 is a sectional side elevation thereof. Fig. 3 is an elevation looking at one end of the machine to show the worm-gearing for driving the reel or spool. Fig. 4 is a vertical cross-section on the line 4 4 of Fig. 2 looking in the direction of the arrow. Figs. 5 and 6 are vertical cross-sections in the 65 planes of the dotted lines 5 5 and 6 6, respectively, on Fig. 2, each view looking in the direction of the arrow. Figs. 7 and 8 are detail cross-sectional views on the lines 7 7 and 8 8, respectively, on Fig. 6. Fig. 9 is a detail view of a part of the feed mechanism. Fig. 10 is a cross-section on the line 10 10 of Fig. 2 looking in the direction of the arrow. Fig. 11 is an enlarged perspective view of the header-lever removed from the machine. Fig. 12 is a similar view of the lever for the 70 movable pointing or forming die. Fig. 13 is another perspective view which illustrates the means for supporting the stationary pointing or forming die. Fig. 14 is a detail view 80 of the nail-strip or string-nails produced by the machine. Figs. 15, 16, and 17 are enlarged detail views illustrating the various positions of the dies during the operations of feeding the stock material, compressing the 85 latter at predetermined regular intervals, so as to produce the desired shape and point to the nails, and of forming the heads on the nails individually, so as to produce the desired string of nails.

90

The same numerals of reference denote like parts in each of the several figures of the drawings.

5 designates the horizontal bed or table, which is supported at a proper elevation by 95 a skeleton framework 6, the latter being erected upon or forming a part of the column 7. This framework may be of any desired character, and I do not, therefore, restrict myself to the particular construction herein 100 shown as one means for supporting the operative parts of the machine. From opposite end portions of the table depend the hangers 8 8^a, having suitable journal-bearings for the

accommodation of the horizontal driving-shaft 9, said shaft extending at one end beyond the frame for the reception of the fast pulley 10, the loose pulley 11, and the balance-wheel 12. An inclined standard 13 extends upwardly from the other end portion of the bed or table, and in a suitable shaft-bearing on said standard is arranged the spool-shaft 16, the latter carrying the spool or drum 17, on which is coiled the strip of continuous nails manufactured by the machine from a single strand of stock material, such as wire. The drum or spool 17 is made fast with the shaft 16, which is supported by the standard in an elevated horizontal position above the table or bed, and on this shaft 16 is firmly secured a driving-pulley 18, around which passes a crossed belt 19, which also encompasses a driving-pulley 20. Said pulley 20 is made fast with a horizontal counter-shaft 21, that is arranged at right angles to the main shaft 9, preferably below the latter. This counter-shaft is journaled in a proper bearing 22 of a bracket 23, which is shown by Fig. 3 as forming a part of one of the hangars 8. One end portion of this counter-shaft 21 terminates below the main shaft 9, and on this last-named shaft is formed or secured a worm-screw 24, the same arranged to have intermittent meshing engagement with a worm-gear 25, which is made fast with the counter-shaft. The rotation of the main shaft 9 turns the worm-screw 24, which in turn propels the counter-shaft 21 through the worm-gear 25, and this shaft drives the pulley 20, the belt 19, and the pulley 18, whereby the shaft 16 is positively driven in order to wind the strip of nails on the spool or drum 17 as rapidly as the nail-strip is produced by the machine.

The table 5 is provided with a short longitudinal slot 26, another longitudinal slot 27, and a cross-bar 28, the latter serving to separate the two slots 26 27. On this cross-bar is arranged the die-block 29, the same being shown in detail by Fig. 13. Said die-block is provided with the parallel wings 30, which are disposed on opposite sides of the block and are joined thereto by the base-plate 31, from which depends the stem 32, that is arranged to pass through an opening 33 of the cross-bar, as shown by Fig. 2. A nut 34 is screwed on a threaded lower portion of the stem 32 and is adapted to fasten the die-block in a stationary position on the bed 5, one of the vertical faces of this die-block being in flush relation to an edge of the cross-bar 28.

The wings 30 are parallel to the lateral faces of the die-block 29, so that the parts will be spaced to provide openings or recesses adapted to receive the under portion of the irregularly curved or shaped die-lever 35, (shown more clearly by Figs. 2 and 12,) and through the wings, the die-block, and the lever passes a pivotal shaft or bolt 36, whereby said lever 35 is fulcrumed on the stationary die-block. The die-block 29 is provided, furthermore, with an upstanding lug 37, in which is pro-

duced a guide-opening 38, and, furthermore, the portion of the die-block which is opposite to the feeder-lever, to be presently described, is recessed or cut away at 39 in Figs. 2 and 13, so as to provide a space for the feeder-plate on the feeder-lever to work therein, all as will hereinafter appear. Finally, the vertical face of the die-block 29, which is flush with one edge of the bar 28, is provided with a dovetailed guideway 40, in which is fitted the lower stationary die of the pair of coacting shaping-dies 41 42. The lower shaping-die 42 rests in a dovetailed guideway of the die-block 29, so as to be supported normally in operative position by a ledge or shoulder of said die-block, as clearly shown by Fig. 2, the upper operative end of said stationary shaping-die being presented in the path of the wire or other stock material as it passes through the lug 37 of the die-block 29.

The shaping-die lever 35 is arranged in a generally-inclined position, so as to have its lower portion arranged and free to work in the slot 27 of the bed 5, and this lever is fulcrumed at a point intermediate of its length on the stationary die-block 29 and its wings 30 by the pivotal shaft or arbor 36. The other upper portion of this shaping-die lever is extended in a vertical direction, as shown by Fig. 2, above the fulcrum 36 thereof, and in this upstanding extremity of the lever is a dovetailed guideway 43, the same receiving the upper movable shaping-die 41, which is held in position adjustably in the lever 35 by suitable clamping and adjusting screws 44 45. The screw or screws 44 is adapted to impinge a side edge of the die 41, while the other screw 45 engages with the upper end of the die for the purpose of giving adjustment to the die in a vertical direction, whereby the upper die may be adjusted to bring the working faces of the pair of coacting shaping-dies into operative relation. These dies 41 42 are provided in their opposing edges or faces with the tapering grooves or channels 46, which are arranged to register with each other, as shown by Figs. 15 to 17, inclusive, and which form a tapered passage on closure of the dies, the greatest diameter of which passage is on the receiving side of the dies just next to the feed mechanism.

The shaping-die lever 35 is provided with the longitudinal slot 35^a, by which it is adapted to receive the fixed die-block 29, thus making provision for compact assemblage of the lever 35 and said die-block. The lower end of this lever carries a shoe 47 in the form of a friction-wheel, which is loosely mounted thereon, as shown by Fig. 2, and this shoe is adapted to ride upon the periphery of a cam 48, the latter being firmly secured to the shaft 9 for rotation therewith. This cam is provided with two high points arranged to successively engage with the shoe 47 and to actuate the shaping-die lever twice on each complete rotation of the shaft.

The machine which I have devised is

equipped with an ordinary straightener mechanism, which is adapted to take the crimp out of the wire as it is fed to the machine and to serve as the means for automatically straightening the wire before it is passed by the feed mechanism to the shaping and heading mechanisms. This straightener mechanism contemplates the employment of a base-plate 49, which is secured in a horizontal stationary position above the bed 5, and on this plate are the series of grooved rolls 50, arranged in groups on opposite sides of the line of feed of the stock material and adapted to engage therewith.

15 I will now proceed to describe the feed mechanism, which has its operative parts disposed between the straightener mechanism and the elements of the shaping-die mechanism. An essential part of this feed mechanism is the 20 upright feeder-lever 51, which is arranged to play in the slot 27 of the table and the slot 35^a of the shaping-die lever 35. This feeder-lever extends in a downward direction past the main shaft 9, and it is bent at a point intermediate of its length, as at 52, (see Fig. 5,) in order that the lower portion of the feeder-lever may be disposed in a different vertical plane from the upper portion of the same lever. This bending of the feeder-lever enables its lower portion to clear the main shaft 9, while its upper portion is disposed close to the path of feed of the stock material or wire, whereby the feeder-lever is adapted to support the wire-engaging devices 35 in proper position for operation. The lower portion of said feeder-lever is fulcrumed by a bolt or pin 53 to a stationary bracket 54, the latter being supported by the framework or the column. A shoe-supporting bracket 55 40 is secured firmly to the feeder-lever, adjacent to the bend 52 therein, and in this bracket is journaled a shoe or roller 56, the same being free to turn on a vertical axis and disposed in the path of the high point on a rotary cam 57, the latter being fast with the shaft 9 and disposed adjacent to the cam 48, which actuates the shaping-die lever 35. The feeder-lever is limited in its movement in one direction by means of an adjustable stop-rod 50 58, the latter being loosely fitted in a short post 59, which is made fast to the bed 5 and serves to support the straightener-plate 49. This stop-rod is secured adjustably to the post by a clamping-screw 60, and the end of 55 the stop-rod lies in the path of the feeder-lever 51. A coiled retracting-spring 61 is fitted loosely on the adjustable rod, one end of the spring being attached to the post 59 and the other end thereof being secured to 60 the feeder-lever, as shown by Figs. 2 and 9, whereby the spring is arranged to normally pull the feeder-lever toward the stop-rod and maintain the shoe 56 in the path of the feeder-actuating cam 57.

55 The feeder-lever has its upper portion extended above the path of the wire or stock material which passes through the straight-

ener, and in said upper portion of this lever is loosely mounted a short pin or bolt 62. Through an enlarged portion of this pin or bolt is an opening that accommodates the feed-finger 63, which is held securely to the rocking pin by a set-screw 64. (See Fig. 5.) This pin 62 is mounted in the feeder-lever, so as to rock or turn on a horizontal axis, 70 while the finger 63 is arranged in an inclined position, so as to engage with the top edge of the wire or stock material. This finger is kept in its operative position by the energy of a coiled retracting-spring 65, one end of which is attached to the feeder-lever, while the other end is secured to an arm 66, which extends outwardly from the rocking pin or bolt, as shown by Fig. 9. A feed-plate 67 is secured firmly to the feeder-lever and disposed in a horizontal position just below, but very close, the path of feed of the wire or stock material. This feed-plate projects from the lever 51 into the space or recess 39 of the die-block, (see Fig. 2,) and this feed-plate is 85 thus mounted on the feeder-lever to partake of the vibrations thereof, and it is maintained at all times in operative relation to the working end of the spring-actuated feed-finger 63. The energy of the spring 65 is sufficient to 90 make the finger 63 and the plate 67 engage with the wire by frictional contact and feed the latter to and through the shaping-die when all the dies are open and the proper movement is given to the feeder-lever by the cam 57; but 95 when the dies (one or both sets) are firmly engaged with the wire, the feeder-lever may be restored to its position by the retractile energy of the spring 65, whereby the feeder-lever is positively moved by the cam in a direction to advance the wire; but the return movement of the feeder-lever to its initial position is effected by a spring, the finger 63 slipping idly over the wire during such return movement of the feeder-lever. 100

68 designates a swinging frame normally arranged in a horizontal position above the slot 26 in the bed 5, said frame consisting of parallel side bars united by an intermediate cross-bar, as shown by Fig. 1. A pivotal arbor 69 passes through one end of the frame, and the end portions of said pivotal arbor are fitted in vertical slots 70, which are formed in the bearing-blocks 71 71^a, the latter being firmly secured on the table 5 at one side of 105 the slot 26 and serving to hingedly connect the swinging frame to said table. The pivotal arbor 69 is capable of adjustment in a horizontal direction by means of the opposing set-screws 72 73, which are mounted in the 110 bearing-blocks on opposite sides of the arbor and are arranged to engage therewith so as to shift the arbor to different positions with respect to the bearing-blocks for a purpose which will hereinafter appear. Through the inner 115 portion of the swinging frame which overhangs the slot 26 and the table 5 loosely passes the upper portion of the header-lever 75, the same being shown more clearly by Fig. 11. 120

Said header-lever is fulcrumed at a point intermediate of its length in the free portion of the swinging frame by the transverse rod or arbor 76, which passes through said frame 5 and the header-lever, whereby the arbor 76 and the swinging frame serve as a shifting fulcrum for the header-lever. The utility of this construction and arrangement will appear in connection with the description of 10 the header-dies.

The header-lever is disposed normally in a vertical position, so as to extend through the slot 26 of the bed and to extend into the frame. The lower portion of said lever is 15 formed with the ring or annulus 77, through which the shaft 9 is free to pass, and this ring or annulus is of such a diameter as to permit the lever to have the desired movement without engaging with the shaft. Above 20 this ring the header-lever is provided with a longitudinal way 78 for a cam-actuated slide 79, the way and the slide being dovetailed in cross-section, as shown by Fig. 8. Furthermore, the upper extremity of the lever 75 has 25 a lateral offset 80, the same being formed with a die-socket 81 and provided with clamping and adjusting screws 82 83. The slide 79 is free to have rectilinear reciprocating movement in the guideway of the header- 30 lever, and said slide is provided at its upper portion with a die-socket 84, the same being dovetailed in cross-section and terminating in a lip or shoulder 84^a.

85 86 designate the coacting header-dies, 35 which are mounted in the die-sockets 81 84, respectively. The upper header-die 85 is engaged by the clamping-screw 82, so as to be held in position thereby, although the clamping-screw may be released and the screw 83 40 may be rotated for the purpose of giving a desired adjustment to the upper die 85. The other or lower header-die 86 is fitted in the socket 84, so as to rest upon the ledge or shoulder 84^a, and said lower die 86 may be 45 held securely in position by a clamping-screw 87. (See Fig. 8.) The active ends of the two header-dies 85 86 are formed with the grooves 88, which are inclined across the faces of the dies and arranged in position to match 50 or register with each other, and the receiving ends of these grooves are enlarged slightly, as at 89, while the delivery-faces of the dies are formed with enlarged clearance-recesses 90. The grooved working faces 88 of the 55 coacting operating-dies conform to the active ends of the shaping-dies, so that the header-die may firmly engage with the work after the shaping-dies shall have given the desired shape or taper thereto; but the head-forming 60 enlargements 89 of the header-dies are adapted to allow the upset metal to enter therein when the pair of closed header-dies are moved positively toward the closed shaping-dies for the purpose of forming the head of one nail 65 constituting the strip or string of nails. The recesses 90 at the back face of the header-dies allow ample clearance for the head of

the newly-formed nail constituting one of the string. (See Figs. 15 to 17, inclusive.)

The lower portion of the slide 79 is provided 70 with a roller-shoe 91, which is loosely mounted on a pin 92, that is attached to the slide, whereby the roller-shoe is disposed above the annular opening 77 of the header-lever. This shoe 91 of the slide is arranged to ride upon a cam 75 93, which is made fast with the main shaft 9 and is adapted to positively lift the slide 79 for the purpose of closing the dies 85 86.

The lower portion of the header-lever is provided with a bolt 94, on which is loosely 80 mounted a roller-shoe 95, the same arranged below the annular opening 77 of said lever and arranged to ride upon the lower portion of the cam 93. The lower portion of the header-lever is furthermore provided with an angular outstanding bracket 96, the same extending beyond the roller-shoe 95 and supporting another roller-shoe 97, the same arranged to rotate on a vertical axis and presented in operative relation to the high parts of a cam 98, 90 which is made fast with the main shaft 9 at a point adjacent to the other cam 93, as clearly shown by Fig. 2. A retracting-spring 99 has one end connected by a link 100 to the lower portion of the header-lever, the other end of 95 said spring being connected to an upstanding arm 101 on a plate 102, which is fastened adjustably by the bolt 103 to the frame of the column. This spring 99 is adapted to pull the lower portion of the header-lever toward the cam 98 in order that the horizontal roller-shoe 97 may ride against the face of the header-lever-actuating cam 98.

From the foregoing description, taken in connection with the drawings, it will be noted 105 that the roller-shoe 91 of the header-slide 79 and the roller-shoe 95 of the header-lever are arranged to ride against the opposite portions of a header-actuating cam 93, and these roller-shoes are caused to follow the movement of 110 the cam by means of a powerful bent spring 104, the same having one end portion attached to the header-lever, as clearly shown by Fig. 2. The tendency of the spring is normally to impel the slide in a downward direction and 115 to lift the header-lever in an upward direction, whereby the roller-shoes are made to ride against the cam. Furthermore, it will be observed that the upper header-die 85 is mounted directly on the header-lever, whereas 120 the lower header-die 86 is supported indirectly on the header-lever through the medium of the header-slide 79, whereby both of the header-dies are adapted to travel with the header-lever when the latter is moved on 125 a horizontal axis by the action of the header-lever-actuating cam 98; but at the same time the lower header-die 86 and the header-slide 79 are capable of a limited movement in a vertical path, such limited movement 130 being independent of the to-and-fro movements of the header-lever. The independent movement of the lower header-die 86 and the slide 79 under the action of the

cam 93 effects the opening and closing of the coacting header-dies, whereby they are made to firmly grip and release the work, and the movement of the header-lever, with the two header-dies thereon, toward the pair of relatively stationary coacting shaping-dies 41 42 has the effect of upsetting the metal of the wire at a predetermined point, whereby the head is formed automatically on the wire or the embryo nail of the string. On opening the pair of shaping-dies and the pair of header-dies the feed mechanism becomes active to advance the wire a distance slightly greater than the length of the nail about to be formed, and one of the problems which has presented itself in the production of this machine is to secure ample clearance for the head of the nail through and between the header-dies. This problem has been solved in the present invention by mounting the header-lever on a shiftable fulcrum which is afforded by the swinging frame and by the employment of a spring, such as 104, which has a tendency to impart a slight upward impulse to the header-lever and to the upper header-die 85 when the header-lever moves backward to its normal position from the heading position, whereby the spring 104 serves to quickly separate the two header-dies 85 86, thus making provision for the easy passage of the nail-head through and between the dies.

The header-lever 75 is provided with a transverse opening 105 and with a bell 106, through which the spring-nails are free to pass on their way to the winding drum or spool.

By making the stop-rod 58 adjustable with relation to the feeder-lever the amplitude of the stroke of said feeder-lever may be varied for the purpose of increasing or decreasing the length of the nails. The adjustment of the pivotal arbor 69 for the swinging frame, which affords the shiftable fulcrum for the header-lever, also allows the parts to be adapted for making nails which may vary in length, and the adjustment of the plate 102 provides for variation in the strength of the spring 99, that normally draws the header-lever 97 into the path of the header-actuating cam 98.

The operation of the machine may be briefly summarized as follows, reference being had more particularly to Figs. 15, 16, and 17: With the two sets of shaping-dies and heading-dies in the open position (shown by Fig. 15) the cam 57 rides against the friction-roller 56, so as to impel the feeder-lever 51 toward the stationary die-block, and the feed-plate 67 and the feed-finger 63 coöperate one with the other in gripping the wire, so as to advance the latter a distance slightly greater than the nail about to be formed, this excess in the length of the wire over the length of the embryo nail allowing for the upsetting of the wire necessary to form the nail-head. Immediately after the advancement of the

wire by the action of the feed mechanism the cam 48 becomes active, so as to move the lever 53 and the upper shaping-die 41 in a downward direction, thereby closing the pair of shaping-dies 41 42 (see Fig. 16) upon the material with such force and pressure as to compress the material for a given length thereof and produce the desired shape and taper to the nail by compression of the stock instead of cutting, abrading, or otherwise removing the material, which would have a tendency to weaken the product, whereby an improved product is produced, because the wire is compressed to the desired tapered appearance. The roller-shoe 47 of the shaping-die lever rides upon the cam 48 for a period to hold the shaping-dies 41 42 gripped upon the material during the period of operation of the header-dies to upset the material. The cam 93 actuates the roller-shoe 91 of the slide 79, so as to close the header firmly upon a previously-shaped portion of the wire, and the cam 98 also rides against the roller-shoe 97, so as to move the header-lever in a direction contrary to that of the line of feed of the material under the action of the feed mechanism. This movement of the header-lever is toward the set of relatively stationary shaping-dies. Such movement takes place when the header-dies are firmly gripped upon the material, and the header-dies and the header-lever are actuated simultaneously, so as to make the header-dies assume the close position to the shaping-dies, (indicated more clearly by Fig. 17,) whereby the metal is upset and enters the recesses 89 in the header-dies, so as to complete the formation of the nail. All the dies are now opened quickly by the roller-shoes riding upon the let-off portions of the cams, so that said dies will return to the position shown by Fig. 15, the header-dies and the header-lever 75 partaking of the peculiar movement heretofore described, so as to afford ample clearance to the passage of the nail-heads. The feed mechanism again becomes active by reason of this cam riding upon the roller-shoe 56, and the product of string-nails is wound upon the drum or spool by the rotation imparted thereto by the described train of gearing.

Changes within the scope of the appended claims may be made in the form and proportion of some of the parts while their essential features are retained and the spirit of the invention is embodied. Hence I do not desire to be limited to the precise form of all the parts as shown, reserving the right to vary therefrom.

Having thus described my invention, what I claim as new is—

1. In a nail-making machine of the class described, a nail-forming mechanism limited to two sets of dies, one of said sets of dies having its members formed to point the nails by a compression action solely on the wire, and the other set of dies having head-forming die-recesses in their coacting faces and in the

faces which oppose the point-compressing dies, combined with means for intermittently and positively reciprocating the set of head-forming dies, while they are gripped upon the wire, in a direction contrary to the feeding of the wire and into coöperative relation to the set of nail-pointing dies, to upset the wire at intervals and form the nail-heads, substantially as described.

10. 2. In a nail-making machine of the class described, a nail-forming mechanism limited to two sets of dies, one of which occupies a stationary relation to the other and said relatively stationary dies formed and driven to point and shape the nails by a compression action solely on the wire, and the other set of dies provided with head-forming die-recesses in the coöperative faces thereof and in the faces which oppose the point-compressing dies, combined with means for opening and closing each set of dies intermittently, and means for positively forcing said header-dies, while gripped upon a wire, toward and in coöperative relation to, the relatively stationary shaping-dies, whereby two sets of dies operate on a wire to head and point the nails, as set forth.

3. In a nail-making machine, the combination of a set of relatively stationary shaping and pointing dies, another set of independent header-dies having gripping-faces and head-forming die-recesses, die-actuating means whereby the dies of each set may be forcibly gripped upon the stock, and quickly opened prior to advancement of the stock, and means for positively moving the set of header-dies toward the shaping and pointing dies and for lifting said header-dies on the return movement thereof, whereby the header-dies are given ample clearance for the nail-heads, substantially as described.

4. In a nail-machine, the combination of a set of coacting dies provided with means for opening and closing the same, another set of dies having their active faces fashioned to point the nails or tacks by a compression action and also provided with means for opening and closing said dies, an intermittent feed mechanism effective to advance a wire in one direction when both sets of dies are opened, and means for positively moving one set of dies toward the other set of dies at a period when both sets of dies are closed and gripped upon the wire, such movement of the dies being in a direction contrary to that of the wire under the action of the feed mechanism, substantially as described.

5. In a nail-machine, a relatively stationary die-block, a lever fulcrumed on the die-block and provided with a roller-shoe, coacting dies mounted in the die-block and the lever respectively and provided with grooves in their opposing faces, and a cam arranged to ride against the heel of said lever and thereby positively move the latter to open and close said dies, in combination with a feed mechanism, a set of coacting header-dies, and means

for positively moving said header-dies in a direction contrary to the line of feed of the work, substantially as described. 70

6. In a nail-machine, the combination with coacting shaping-dies, and a slotted lever for opening and closing said dies, of a feeder-lever passing through the slotted lever and provided with a roller-shoe, a cam arranged 75 to ride against said shoe, a spring connected with the feeder-lever for holding the same in a retracted position, an adjustable stop in the path of the feeder-lever, and coöperating work-engaging devices movable with the co-acting header-dies, substantially as described.

7. In a nail-making machine of the class described, the combination with nail-pointing mechanism, and a suitable feed mechanism, of a header-die support mounted on a 80 shiftable fulcrum and capable of a compound movement whereby it may be positively moved toward the pointing mechanism and it may be raised or lifted somewhat on its return movement, coacting header-dies mounted in 85 the support for movement therewith, means for closing said header-dies and for opening the same prior to, or simultaneously with, the upward and return movement of the header-die support, and means for giving the shift- 90 ing movement to said header-die support, substantially as described.

8. In a nail-machine, the combination with shaping-dies, and a feed mechanism, of a header-lever, a slide mounted thereon, coöperating header-dies mounted on the lever and the slide respectively, means for actuating the slide to open and close said dies, and means for moving the header-lever to shift the position of the header-dies in a direction contrary 105 to the line of feed of the work, substantially as described.

9. In a nail-machine, a header-lever, a slide movable thereon, and a retractor connecting the lever and the slide to impart relative movement to the same in opposite directions, and header-dies mounted on the lever and the slide respectively, and a cam having operative engagement with the lever and slide, in combination with shaping-dies, and means for moving 110 the header-lever and the dies thereon toward or from said shaping-dies, substantially as described.

10. In a nail-machine, the combination of a header-lever, a shiftable support for said header-lever, a slide limited to rectilinear movement on the header-lever, coöperating header-dies mounted on the lever and the slide respectively, a cam in operative relation to the lever and the slide, and a spring connecting the lever and slide, in combination with shaping-dies and means for imparting movement to the header-lever and the header-dies contrary to the direction of the feed of the work, substantially as described. 120

11. In a nail-machine, the combination of a header-lever provided with roller-shoes 95, 97, a slide on said header-lever and provided with a roller-shoe 91, a cam disposed between the

slide-shoe and one shoe of the header-lever, another cam in operative relation to the other shoe of the header-lever, a retractor connecting the lever and the slide, coöperating header-dies mounted on the lever and the slide, a shiftable support for the header-lever, a set of shaping-dies, and a feed mechanism, substantially as described.

12. In a nail-machine, the combination of a header-lever, a swinging frame pivoted to the header-lever, means for adjustably supporting the swinging frame in pivotal relation to the header-lever, a set of header-dies carried by said header-lever, means for opening and closing said dies, a set of shaping-dies, and means for moving the header-lever and the header-dies toward or from the shaping-dies, substantially as described.

13. In a nail-machine, the combination of a header-lever, a shiftable support for said header-lever, two roller-shoes mounted on the lower portion of the header-lever, a cam having operative relation to one of said shoes, an adjustable plate, a spring connected to the header-lever and to said plate and adapted to normally position said roller-shoe in the path of said cam, a slide mounted on the header-lever and provided with a roller-shoe, another cam disposed between the roller-shoes of the lever and the slide, the coöperating header-dies on the lever and the slide, and a set of shaping-dies, substantially as described.

14. A nail-machine in which the pointing and heading devices are restricted to two sets of dies, one set of dies occupying a non-shiftable position and opened or closed by cam-actuated devices, the other set of dies being provided with active faces arranged to point the nails by a compression action, a header-lever arranged to positively move one set of dies toward or from the other set, and a cam in operative relation to the header-lever, substantially as described.

15. In a nail-machine, the combination of a set of dies, another set of dies, cam-actuated

means for opening and closing each set of dies, a header-lever arranged to positively advance one set of dies relative to the other set and at a period when both sets of dies are closed, a cam arranged to actuate the header-lever, and an intermittently-active feed mechanism operable to advance a wire during the period when both sets of dies are opened, such advancement of the wire being in a direction contrary to the heading movement of the set of dies by the header-lever, substantially as described.

16. In a nail-machine, the combination of two sets of independently-mounted dies, a main shaft having a plurality of cams, means actuated by certain cams to open and close said dies, a feeder-lever actuated by another cam and having means for feeding a wire through said dies when the latter are opened, and a header-lever actuated by a cam on said main shaft and operatively connected with one set of dies to positively move the latter in a direction contrary to the line of feed by the feeder-lever and at a period when both sets of dies are closed upon the wire, substantially as described.

17. In a nail-machine, the combination of a main shaft having a plurality of cams, an upright feeder-lever actuated by one of said cams and having means for gripping and feeding a wire, an upright header-lever also arranged for actuation by one of said cams, two sets of dies independently mounted, one set being movable with the header-lever in a direction contrary to that of the wire under the action of the feeder-lever, and cam-actuated devices for opening and closing the dies of said sets, substantially as described.

In witness whereof I have hereunto set my hand in the presence of two witnesses.

NAPOLEON DUSSAULT.

Witnesses:

H. F. BERNHARD,
JOHN F. DEUFFERWIEL.
